UNITED STATES PATENT OFFICE.

GEORGE WILLIAM WILKINSON, OF WEST RUTLAND, VERMONT.

CAR-AXLE.

SPECIFICATION forming part of Letters Patent No. 319,369, dated June 2, 1885.

Application filed March 12, 1885. (No model.)

To all whom it may concern:

Be it known that I, GEORGE W. WILKINSON, of West Rutland, in the county of Rutland and State of Vermont, have invented a new and Improved Car-Axle, of which the following is a full, clear, and exact description.

The object of my invention is to provide a practical car-axle constructed to permit the wheels to have independent movement; and the invention consists of the construction, arrangement, and combination of parts, all as hereinafter described and claimed.

Reference is to be had to the accompanying drawing, forming part of this specification, in which the figure is a longitudinal sectional elevation of my new car-axle, the car-wheels being shown in dotted lines.

The axle A is composed of two main parts, the inner shaft portion, a, and the outer shell, b, that surrounds the shaft a. The shaft a has the point a' formed at one end, while the shell b has the point b' coupled to it by the coupling flanges or plates c and c', secured, respectively, (by screw-threads or otherwise,) to the adjacent ends of the shell b and point b', and bolted together by the bolts d. The shaft a is secured from endwise movement in the shell b by the collar e, screwed upon the shaft a, which collar is of slightly-larger diameter than the shell b, and is inclosed by the coupling-plates c c', as shown in the drawing.

Between the end of the shell b and the collar e, I place upon the shaft a the washers f f, to protect the inner surface of the collar e from wear.

The inner end of the point b' is provided with the head b'', and between this head and the end of the shaft a and collar e, I place the washers g g', which take the friction, and which can be replaced at small cost when worn. The head b'' is made adjustable to take up the wear of the plates g g' by the long set-screw h, fitted in the screw-threaded opening h', made through the center of the point b'.

The shaft a has three bearings, i, in the shell b, and the shaft has the central opening, j, and side opening, j', formed in it for oiling the said bearings i. The collar e and plates g g' and head b' are oiled from the said oil-passage j through the diagonal opening l, made in the plate g'. When the passage j is filled with oil, escape of it is prevented by the oil-cup k, fit-

ted in the outer end of the shaft a, and the outer end of the shaft a is chambered, as shown at a', to receive the oil-cup.

The oil-cup k is composed of the sleeve m, screwed into the end of the axle, the tube m' placed in the sleeve m, and the coiled spring m², placed upon the tube m', to act between the outer flange, m³, of the tube and the outer surface of the sleeve m. The tube m' is held in the sleeve m by the flange m⁴, that closes the inner end of the tube m', and is larger in diameter than the sleeve m. Several holes, n, are made in the tube m', to permit oil to pass from the tube m' into the cavity a², which will take place only when the tube m' is pressed inward against the pressure of the spring m² until the holes n pass the inner end of the sleeve m. In oiling, the tube m' will be pressed inward by the spout of the oil-cup, and as soon as the oil-cup is removed the spring k will automatically close the cup, so that there will be no escape of oil.

Constructed as described, it will be seen that the wheels keyed upon the points of the axle are permitted to revolve independently of each other, which is of great practical advantage in avoiding wear and tear upon the oilers and excessive friction in rounding curves.

Having thus described my invention, what I claim as new, and desire to secure by Letters Patent, is—

1. The shaft portion a, provided with the collar e, in combination with the shell b, coupling-plates c c', and the point b', the coupling-plate c being secured to the shell b, the plate c' to the point b', substantially as described.

2. The combination, with the separate point b', shaft portion a, and coupling-plates c c', of the adjustable block or head b'', arranged substantially as and for the purposes set forth.

3. The point b', provided with the screw h, in combination with the adjustable block b'', substantially as described.

4. The shaft portion a of the axle, in combination with the shell b and bearings i, said bearings being interposed between said shaft portion and shell, substantially as described.

5. The shaft portion a, provided with the central oil-opening, j, and side oil-passages, j', for conducting the oil to the bearings i, substantially as described.

6. The shaft portion a, provided with the

oil-passage *j*, in combination with the washers *g* and *g'*, the latter being formed with the diagonal oil-passages *l*, substantially as described.

5 7. The shaft portion *a*, provided with the oil-passage *j*, in combination with the self-closing oil-cup *k*, fitted in its outer end, substantially as described.

8. The shaft portion *a*, formed with oil-passages *j* and recess *a'*, in combination with the

sleeve *m*, tube *m'*, and spring *k*, the tube being placed in the sleeve *m* and formed with the openings *n*, and provided with outer and inner flanges, *m³* *m⁴*, substantially as and for the purposes set forth.

GEORGE WILLIAM WILKINSON.
